UNITED STATES PATENT OFFICE.

OSWALD H. HANSEN, OF PORT WASHINGTON, WISCONSIN, ASSIGNOR TO GILSON MANUFACTURING COMPANY, OF PORT WASHINGTON, WISCONSIN, A CORPORATION OF WISCONSIN.

CHAIR.

Application filed November 28, 1921. Serial No. 518,244.

To all whom it may concern:

Be it known that OSWALD H. HANSEN, a citizen of the United States, residing at Port Washington, in the county of Ozaukee 5 and State of Wisconsin, has invented a certain new and useful Chair, of which the following is a specification.

This invention relates in general to improvements in the art of manufacturing articles of furniture, and relates more specifically to improvements in the construction of tilttable revolving chairs and the like.

A general object of the invention is to provide a chair which is simple in construction 15 and efficient in operation. Another general object of the invention is to provide improved seat supporting structure for tilttable revolving chairs.

Most of the prior commercial "chair irons" for tilting revolving chairs are objectionable since they embody in their assemblage, at least one or more cast metal elements. Due to the rough handling to 20 which chairs of this type are often subjected, the cast metal elements are frequently broken thereby disabling the chair and necessitating renewal of the broken parts. The tilting chairs of the prior art are moreover squeaky in operation even when frequently lubricated, the squeaking being due 25 to the fact that the springs are displaced transversely of their axes during tilting of the seat. A further serious objection to the prior chairs of the revolving type, is that 30 they cannot be readily dismantled for storage and shipment, and reassembled in order to make them ready for use. Still another objection to prior commercial "chair irons" is their high cost of manufacture, it being 35 customary to provide for the higher grade chairs, supporting structures which are of entirely different design and construction 40 from those employed in the lower grade chairs. These are only a few of the defects in construction and operation of the tilttable revolving chairs of the prior art, which have made such devices generally unsatisfactory and inefficient in operation.

The present invention contemplates the 45 provision of a seat supporting structure for tilting revolving chairs and the like, which may be properly termed a "chair steel" since the use of cast elements and iron are entirely eliminated: which is exceedingly

quiet in operation regardless of neglect in 55 its lubrication; which may be readily and quickly dismantled and assembled whenever desirable; which may be manufactured and sold at minimum cost; and which is sufficiently neat and compact in appearance 60 to enable its utilization on chairs of any grade.

Some of the more important specific objects of the present invention may be enumerated as follows:—To provide a seat support for chairs, which is simple and rugged in its construction and which will present a neat and highly finished appearance. To provide a chair support which enhances the comfort afforded by using the chair, and 70 which permits rapid and convenient adjustment of the height of the seat and of the degree of effort necessary to tilt the seat. To provide a chair supporting structure which may be readily assembled and dismantled, and all parts of which are accessible. To provide a "chair steel" various elements of which may be manufactured at 75 minimum cost, from sheet steel and with the aid of dies thereby making these elements 80 interchangeable. To provide a support for chairs, the elements of which cannot be readily broken, thereby insuring maximum service. To provide numerous other improvements in the details of construction of 85 tilttable and revoluble chairs which will minimize the cost of manufacture of such chairs and which will increase the efficiency of operation of such devices.

Some of the novel features of chair construction, disclosed but not specifically claimed herein, form the subject of the following co-pending applications for Letters Patent:—Serial No. 424,015, filed November 15, 1920; and Serial No. 455,732, filed March 95 26, 1921.

A clear conception of embodiments of the various novel features of the present invention and of the operation of devices constructed in accordance therewith, may be 100 had by referring to the drawings accompanying and forming a part of this specification, in which like reference characters designate the same or similar parts in the various views.

Fig. 1 is a fragmentary part sectional side elevation of a tilttable revolving chair.

Fig. 2 is a bottom view of the upper por-

tion of the "chair steel", which is attachable directly to and which is rotatable with the seat.

Fig. 3 is a top view of the pressed metal standard embracing yoke.

Fig. 4 is a side elevation of the pressed metal standard embracing yoke.

Fig. 5 is a top view of the pressed metal spreader.

Fig. 6 is a side elevation of the pressed metal spreader.

Fig. 7 is a top view of the pressed metal seat adjusting hand wheel.

Fig. 8 is a fragmentary part sectional top view of the chair base.

Fig. 9 is an enlarged side elevation of the rear pressed metal spring supporting bar.

Fig. 10 is an enlarged front view of the rear pressed metal spring supporting bar.

Fig. 11 is an enlarged rear view of the front pressed metal spring supporting bar.

Fig. 12 is an enlarged side elevation of the front pressed metal spring supporting bar.

Fig. 13 is an enlarged central vertical section through the pressed metal spring adjusting hand wheel.

Fig. 14 is an enlarged front elevation of the pressed metal spring adjusting hand wheel.

The tiltable revolving chair illustrated in Fig. 1, comprises in general, a base, a vertical post or standard 4 having its lower portion rigidly secured to the base, a bracket or yoke 5 freely rotatably mounted upon an upper portion of the standard 4, an inverted U-shaped spreader 7 pivotally connected to the yoke 5, spring mechanism for restraining the movement of the spreader 7 relatively to the yoke 5, elongated spider arms 3 rigidly attached to the upper corners of the spreader 7, and a seat 2 attached to the front and rear extremities of the spider arms 3.

The chair base, shown in detail in Figs. 1 and 8, consists of four wooden legs 33 extending radially away from the lower extremity of the steel post 4 and having their inner ends formed to closely fit the standard, a pressed metal top plate 26 having a central upwardly projecting flange 38 snugly fitting and rigidly secured to the post 4 by means of a locking pin 28, a pressed metal bottom plate 27 having a central downwardly projecting cup shaped portion 39 snugly fitting the lower end of the post 4, and wooden filler blocks 32 located in the corners formed by the coacting leg ends. The legs 33 are provided with upper and lower transverse recesses into which the continuous peripheral flanges 34, 35 of the top and bottom plates 26, 27, are located. The continuous flanges 34, 35 of the top and bottom plates 26, 27 may also engage the corners of the adjacent filler blocks 32, which are thus held in place. A hub clamping screw 31 has screw thread engagement with a thread-

ed hole in the lower end of the post 4, and has a head which engages the bottom 29 of the bottom plate portion 39. With this assemblage of elements, it will be noted that as the clamping screw 31 is tightened, the bottom plate 27 is urged upwardly along the post 4 and toward the fixed top plate 26, thereby firmly clamping the legs 33 and the filler blocks 32 between the top and bottom plates 26, 27. It will also be obvious that the hub structure may be readily and completely dismantled by merely releasing the single hub clamping screw 31.

The vertical steel standard or post 4, the lower end of which is rigidly secured to the chair base, has its upper portion screw threaded and provided with an elongated recess 21 in one side thereof, see Fig. 1. A pressed metal seat adjusting hand wheel 14 has a central bore and oppositely located ridges 24 extending into said bore and adapted to coact with the threads on the post 4, see Figs. 1 and 7. The upper central portion of the hand wheel 14 is provided with an annular depression or recess within which a thrust bearing 15 of suitable design, may be located. A locking pin 17 the inner end of which is adapted to engage the recess 21 of the post 4 to lock the wheel 14 against movement about the post 4, is mounted in horizontally aligned holes formed in downwardly distorted portions of the hand wheel 14. The pin 17 is urged toward the recess 21 by means of a helical compression spring 19 one end of which reacts against a surface of the hand wheel 14 and the opposite end of which bears against lateral projections formed on the locking pin 17. The periphery of the hand wheel 17 is provided with a vertical notch 37 for holding the pin 17 in locking position, and has two detents 45 located on opposite sides of the notch 37 for holding the pin 17 in released position. The metal of the hand wheel 14 is also distorted to form a pair of oppositely located lugs 16 which extend inwardly some distance above the thrust bearing recess.

The main bracket or yoke 5 comprises a hub and a pair of parallel vertical side walls 6 projecting forwardly from the hub, see Figs. 1, 2, 3 and 4. The yoke 5 is formed entirely of sheet metal, the rear half of the hub being formed integral with the side walls 6 and the front half comprising a cap 25 which is rigidly secured to the rear half by means of rivets or bolts. The yoke hub embraces and is freely rotatable about the upper portion of the standard or post 4, the hub being provided with a lower laterally projecting flange which rests upon the thrust bearing 15 and extends under the lugs 16 of the adjusting hand wheel 14, thereby preventing extended axial separation of the hand wheel 14 and yoke 5. The side walls 6

of the yoke 5 are provided with lower laterally projecting bosses 36 having aligned openings which provide bearings for a horizontal pivot pin 13. The yoke side walls 6 are also provided with upper elongated slots 18 the opposite ends of which provide abutments for limiting the forward and rearward movement of the chair seat 2. The forward edges of the yoke side walls 6 are provided with spring bar supporting notches 30.

The inverted U-shaped spreader 7 is formed of pressed sheet metal and comprises a pair of parallel side walls and a top connecting plate, see Figs. 1, 2, 5 and 6. The lower portions of the spreader side walls are secured to the pivot pin 13 which is supported by the yoke bosses 36. The top plate of the spreader 7 is distorted to form a downwardly extending flange 22 which stiffens the structure and incidentally forms a recess which permits rearward swinging of the spreader 7 without interfering with the yoke cap 25. The side walls of the spreader 7 are also connected by the cross rod 12 which is riveted to the spreader and passes through the elongated yoke slots 18. The cross rod 12 is adapted to limit the extent of movement of the chair seat 2 by engaging the opposite ends of the slots 18.

The cross rod 12 and the spreader 7 are urged forwardly until the rod 12 engages the forward ends of the slots 18, by means of a pair of helical compression springs 8, the rear ends of which engage the rear pressed metal spring supporting bars 23 and the forward ends of which engage the front pressed metal spring supporting bars 9. The rear spring supporting bars 23 shown in detail in Figs. 9 and 10, are two in number being identical in structure and connected by means of rivets or bolts. Each bar 23 is provided with rear notches 40 adapted to engage the front notches 30 of the yoke side walls 6, and is further provided with a pair of forwardly extending projections 41 adapted to fit within the rear ends of the springs 8. The disposition of the projections 41 is such that the springs have three point contact with the projections and with the adjacent bars 23. The medial portions of the bars 23 are distorted to form an elongated central opening 43. The front spring supporting bars 9 shown in detail in Figs. 11 and 12, are two in number being identical in structure and connected by means of rivets or bolts. Each bar 9 is provided with a pair of rearwardly extending projections 42 adapted to fit within the front ends of the springs 8. The disposition of the projections 42 is such that the springs have three point contact with the projections and with the adjacent bars 9. The medial portions of the bars 9 are distorted to form a circular central opening 44. The spring adjusting

rod 10 has a hooked rear end which engages the cross rod 12, and has a threaded forward end with which the pressed metal spring adjusting hand wheel 11, shown in detail in Figs. 13 and 14, coacts. The rod 12 extends through the central openings 43, 44 of the supporting bars 23, 9.

The spider arms 3 are formed of pressed sheet metal and are rigidly attached to the upper side portions of the spreader 7. The chair seat 2 is rigidly attached to the ends of the spider arms 3 and has its forward portion located above the spreader 7 and the elements associated therewith. The seat 2 is preferably slightly inclined relatively to the horizontal as shown in Fig. 1, when the spreader cross rod 12 engages the forward ends of the slots 18.

During normal use of the chair, the seat 2, spider arms 3, spreader 7 and yoke 5 may be freely revolved about the standard or post 4 upon the thrust bearing 15, without varying the elevation of the seat 2. The weight of the revoluble elements and of the occupant of the chair, is supported by the base through the standard or post 4 and the pressed metal nut 14. The chair seat 2 may be readily tilted rearwardly until the spreader cross rod 12 engages the rear ends of the elongated yoke slots 18, the helical springs 8 being compressed during such tilting of the chair seat 2. Due to the location of the slots 18 directly above the spreader pivot 13, there is but slight vertical displacement of the cross rod 12 and of the adjacent end of the hook rod 10 during tilting of the seat 2. This transverse displacement of the rear end of the hook rod 10 is permitted by the elongated opening 43 in the rear spring supporting bar 41, and does not affect the front end of the rod 10. The springs 8 are held against transverse displacement during tilting of the chair seat 2 by virtue of the interlock between the spring supporting bars 23 and the yoke side walls 6 afforded by the notches 40, 30, and also by confining the movement of the forward spring supporting cross bar 9 to motion of translation.

If it is desired to vary the height of the chair seat 2, the locking pin 17 must be released and the adjusting hand wheel 14 rotated relatively to the stationary post 4. Such rotation of the hand wheel 14 causes the same to advance along the threaded portion of the post 4 by virtue of the engagement of the detents or projections 24 with the screw threads. During such adjustment of the hand wheel 14, the end of the pin 17 may be permitted to rest in one of the notches 45 in the wheel rim, thus retaining the pin 17 withdrawn. When the desired position of adjustment has been reached, the pin 17 may again be turned into alignment with the recess 37 and permitted to enter the recess 21 of the post 4,

whereupon the hand wheel 14 is again locked to the post 4. If it is desired to vary the degree of effort required to tilt the chair seat 2, it is necessary to manipulate the 5 spring adjusting hand wheel 11 relatively to the hook rod 10. By thus adjusting the hand wheel 11, the degree of compression of the springs 8 may be readily varied to suit the desired conditions. Either of these 10 adjustments may be quickly made, the adjusting hand wheels 11, 14 being readily accessible.

It is noteworthy that the use of cast metal elements is entirely eliminated in the 15 assemblage of the chair. The hub plates 26, 27, hand wheel 14, yoke 5, cap 25, spreader 7, spider arms 3, rear bars 23, front bars 9 and hand wheel 11 may all be formed of sheet steel with the aid of dies, thus making 20 these elements interchangeable with like elements of other chairs and eliminating necessity of other expensive machining operations. The post 4, pivot 13, cross rod 12 and hook rod 10 may be readily formed of 25 standard bar steel, thereby permitting the use of steel throughout the structure. It will also be obvious that the same structure may readily be used on chairs of all 30 grades. In the cheaper grades, the chair 35 steel may be coated by painting while in the higher grades, the structure may be given a highly finished appearance by nickel plating. The cheaper structure may also be provided with a plate bearing 15, while the higher grade structure may be provided with a ball bearing 15.

It will also be noted that the entire structure may be readily assembled and dismantled. The legs 33 and the filler blocks 40 32 may be removed by manipulation of the single locking screw 31. The yoke 5 and the associated revoluble elements may be removed from the post 4 by releasing the locking pin 17 and working the hand wheel 45 14 upwardly from the post 4. The hand wheel 14 may then be slipped laterally from the yoke hub flange. The springs 8 and the bars 23, 9 may be removed by unscrewing the hand wheel 11.

50 The detents 24 of the adjusting nut 14 may be formed with the aid of an internal die member which after formation of the local detents 24 may be removed by rotating the die through an angle of 90 degrees. The 55 other elements may be readily formed with simple dies at extremely low cost.

It should be understood that it is not desired to limit the present invention to the exact details of construction herein shown 60 and described, for various modifications within the scope of the claims may occur to persons skilled in the art.

It is claimed and desired to secure by Letters Patent:—

1. In a chair, an upright post, a yoke comprising a hub freely rotatable about said post and a plate extending away from said hub, said hub being formed in sections one of which is formed integral with said plate, and a seat supported on said plate. 65

2. In a chair, an upright post, a yoke comprising a hub freely rotatable about said post and a pair of plates extending away from said hub, said hub being formed of sheet metal sections one of which is formed integral with said plates, and a seat tiltably 70 associated with said yoke. 75

3. In a chair, an upright post, a yoke comprising a hub embracing said post and a pair of plates extending forwardly of said chair and away from said hub, said hub being formed in sections one of which is formed integral with said plates, means for adjusting said hub along said post, and a seat tiltably associated with said yoke. 80

4. In a chair, a base, an upright post rigidly attached to said base, a yoke comprising a hub freely rotatable about said post, said hub being formed in sections laterally united in a plane intersecting said post, means for adjusting said hub along said post, and a seat tiltably associated with one of said hub sections of said yoke. 90

5. In a chair, an upright post, a yoke comprising a hub embracing said post and a plate extending away from said hub, said hub being formed in sections one of which is formed integral with said plate, a seat pivotally supported on said plate, and a stop movable by said seat, said plate having an opening the opposite ends of which are engageable with said stops to limit the pivotal movement of said seat. 95

6. In a chair, an upright post, a yoke comprising a hub freely rotatable about said post and a plate extending away from said hub, said hub being formed in sections one of which is formed integral with said plate, a seat pivotally supported on said plate, and a stop carried by said seat, said plate having an opening the opposite ends of which are engageable with said stop to limit the pivotal movement of said seat. 100

7. In a chair, a base, an upright post, said post being rigidly attached to said base, a yoke comprising a hub freely rotatable about said post and a pair of plates extending forwardly away from said hub, said hub being formed in sections one of which is formed integral with at least one of said plates, a seat pivotally supported on said plates, and a cross rod carried by said seat, said plates having openings the opposite ends of which are engageable with said rod to limit the pivotal movement of said seat. 115

8. In a chair, an upright post, a yoke comprising a hub embracing said post and a pair of plates extending away from said

hub, a seat pivotally supported on said plates, resilient means coacting with said plates, and means connecting said resilient means with said seat, said plates having 5 openings for limiting the pivotal movement of said seat and said openings being penetrated by said connecting means.

9. As an article of manufacture, a sheet metal spring reaction bar for tilttable 10 chairs, comprising a pair of connected plates having their opposite ends bent away from each other to provide three point contact

with the spring ends and having an opening between the medial portions thereof.

10. As an article of manufacture, a pressed 15 sheet metal spring reaction bar for tilttable chairs, comprising two plates having their ends bent away from each other and having their medial portions oppositely distorted to form a through opening. 20

In testimony whereof, the signature of the inventor is affixed hereto.

OSWALD H. HANSEN.
